(57) **CLAIM**

The ornamental design for a magnetic field generator for medical use, as shown and described.

DESCRIPTION

FIG. 1 is a front perspective view of a magnetic field generator for medical use showing the new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a top view thereof.

The following application is for a new, original and ornamental design for a magnetic field generator for medical use, intended to be used together with an endoscope, of which the following is a specification, reference being made to the accompanying drawings, forming a part thereof.
